BOTTLE, CAP, AND BRUSH

Dante J. Nardone, Brooklyn, N. Y., assignor to
 A. Sartorius & Co. Inc., New York, N. Y., a
 corporation of New York

Application October 25, 1945, Serial No. 624,470

1 Claim. (Cl. 15—140.4)

1

My invention relates to a novel article embodying a filled bottle having therein a brush or applicator which is secured to a sealing disk maintained under compression on the bottle neck by a closure cap. Still further, my invention relates to an article formed from a bottle sealing disk and an attached brush or applicator. My invention also relates to a novel sealing arrangement for a bottle.

In accordance with my invention, either manually or by an automatic filling machine, bottles are filled with a desired liquid. Following the filling operation, each bottle has disposed therein a brush or applicator which is secured to a sealing disk adapted to rest on the top surface of the bottle neck. Thereafter, by utilizing suitable mechanism, closure caps are automatically threaded to each bottle neck, each closure cap, during the threading operation, moving into engagement with the bottle-supported sealing disk and compressing the same to effectively seal the bottle.

Various other features and advantages of my invention will become apparent from the following detailed description.

My invention resides in the art of filling and capping bottles, novel arrangements, articles and combinations of the character hereinafter described and claimed.

For an understanding of my invention, reference is to be had to the accompanying drawings, in which:

Figure 1 is a vertical sectional view, partly in elevation, showing a filled bottle having associated therewith a partially seated closure cap;

Fig. 2 is a sectional view showing the closure cap of Fig. 1 in final seated position;

Fig. 2a is an enlarged, fragmentary view showing a feature of the invention; and

Fig. 3 is a diagrammatic view illustrating the method concept of my invention.

Referring to Fig. 1, I have shown a bottle or container 1 having an upstanding neck 2 provided with exterior screw threads 3. Seated on the top of the bottle neck 2 is a sealing disk or washer 4 formed from any suitable material such, for example, as rubber or, preferably, from a more rigid rubber cork mixture as known in the art. The disk 4 may have a central passage which receives one end of a brush or applicator 5, the latter being secured to said disk 4 in any desired manner as, for example, by suitable adhesive such as casein glue. As shown in Figs. 1 and 2, a suitable closure cap 6 is threaded to

2

the bottle neck 2 to close the bottle 1. The attached cap 6 holds the disk 4 seated on the upper surface of the bottle neck and retains the brush 5 within the bottle.

5 In accordance with the invention, empty bottles 1, each without a brush and a closure cap, of the character described above or of such other suitable character as may be desirable pass in succession through an automatic filling machine F, Fig. 3, of a character well known in the art. Each bottle 1, as it passes through the machine F, is filled with a desired liquid and then, in suitable manner, the filled bottles 1 are passed toward a known automatic cap applying mechanism C which may be an attachment of the machine F and which comprise suitable mechanism for feeding closure caps 6 in succession toward the cap-applying position.

With a supply of the above described attached 20 disks 4 and brushes 5 available, one of them is associated with each filled bottle 1 while the latter is between the machines F and C. This may be done by an operator or by suitable mechanism. In so doing, each brush 5 is immersed 25 in the bottle-contained liquid and the associated disk 4 is seated on the top of the bottle neck, Fig. 3. In this condition, each bottle 1 passes to the machine C which functions to thread to the bottle neck 2 a cap 6 which, prior to the threading operation, has neither a sealing disk nor a brush associated therewith. This cap 6, at the conclusion of the threading operation, holds the disk 4 under compression on the top surface of the bottle neck to thereby seal the same. Thereafter, the filled bottles 1, each having a sealing disk 4, a brush 5 and a closure cap 6 associated therewith, are suitably removed from the machine C, labelled and packed for shipment.

40 It will be understood by those skilled in the art that, in practicing my invention as hereinbefore described, numerous advantages result compared with the present practice of producing liquid-filled, brush-containing bottles.

45 Thus, as regards current practice, the cap manufacturer molds plastic material to form closure caps each of which has a small central well or cavity destined to receive the upper end of a brush or applicator handle. Thereafter, a liner or disk corresponding with the hereinbefore described disk 4 and having a central passage is inserted in a cap and, usually but not necessarily, held in position by adhesive.

50 In this condition, the caps and associated liners 55 are forwarded to bottling companies where the

completed filled bottles are produced. At the bottling company, one end of a brush or applicator is passed through the central passage of each liner and secured adhesively in the above described well of the closure cap. As a result, there becomes available a supply of closure caps each of which has a liner or disk together with a brush permanently secured thereto.

At the bottling company, there is an automatic filling machine and an associated automatic cap applying mechanism of the character referred to above. This apparatus functions automatically to fill the bottles and apply a closure cap to each bottle. However, the cap applying mechanism is incapable of handling a closure cap if it has a brush or applicator secured thereto as described above. Hence, if combined closure caps and applicators are to be associated with filled bottles, it is necessary that this be done manually by an operator. This is time-consuming and otherwise disadvantageous by reason of the fact that many bottles are returned by customers due to leakage which develops as a result of improper application of the closure caps to the respective bottles.

As will be understood in view of the foregoing description, it is a feature of my invention that the sealing disk and brush, as a combined unit, are associated with the filled bottle rather than with the closure cap. The latter, then, may readily be applied to the bottle by the automatic mechanism C with resultant elimination of the disadvantages discussed above in connection with the manual operations.

Closure caps utilizable in accordance with my invention have greater simplicity than those used in present practice. This follows due to the omission of the central well which is provided for one end of the brush. In addition, the manufacturer of the closure caps does not insert the sealing liners or disks therein. For these two reasons, then, the cost of the closure cap as supplied by the manufacturer is decreased.

Closure caps utilizable in accordance with my invention may be of any type suitable for the intended purpose and in this connection it will be understood, as stated, that no need arises for the provision of the aforesaid central well. However, preferably, I utilize a closure cap of the character illustrated which, above the threaded area 7 thereof, is shaped to form a circular flange or seat 8 connected at its periphery with a vertical circular surface 9 having an internal diameter only slightly greater than the external diameter of the sealing disk 4 which is to be associated with the closure cap. The height of this vertical surface 9 is somewhat greater than the thickness of the disk 4. The vertical surface 9 of the closure cap merges into a conical or beveled surface 10 and this, in turn, merges into an upper vertical surface 11.

The bottle 1 may be of known construction and, if so, the upper surface of the bottle neck 2 may have plane, circular configuration as indicated at 12 and this plane surface may be bordered by an outer beveled or frusto conical surface 13.

As will be understood, during the threading operation, the closure cap 1 moves downwardly with respect to the bottle neck 2 and the sealing disk 4. Eventually, then, the disk 4 takes a position as illustrated in Fig. 1 where it rests upon the flange 8.

When the closure cap 1 is threaded to its intended seated position as shown in Figs. 2 and 75

2a, the sealing disk 4 is held under compression against the bottle neck surface 12 to thereby seal the bottle opening. At the same time, the beveled surface 10 of the closure cap holds the outer portion of the disk 4 partially folded so that it engages the beveled surface 13 of the bottle neck and extends around the peripheral corner 14 thereof with resultant enhancement of the sealing action. The space 11a defined by the upper vertical surface 11 of the closure cap is provided for the reception of the upper part of the disk 4 when the latter is disposed in its final seated position.

The hereinbefore described operation involving attachment of a sealing disk 4, a brush 5 and a closure cap 6 to a bottle neck causes the sealing disk 4 to move into the closure cap beyond the flange 8 thereof. Subsequently, when a closure cap 6 is unthreaded and removed from its bottle, the disk 4 and brush 5 are also removed with the closure cap. This happens because the disk 4 seats upon the flange 8. Hence, the brush 5 is positively associated with the closure cap and the latter may be manipulated as desired to cause the brush 5 to perform its intended function. If desired, prior to the assembling operation shown in Fig. 3, the periphery of the disk 4 may have suitable adhesive applied thereto whereby said disk 4, after completion 30 of the described assembling operation, becomes more positively secured to the interior surface of the closure cap.

It will be understood that the invention is not to be limited to the precise threaded arrangement shown on the drawing. As well, the threads may be partial or of other equivalent type.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended 45 claim to cover all such changes and modifications.

What is claimed as new and desired to be secured by Letters Patent, is:

An article of the class described comprising a bottle having an externally threaded neck, the upper surface of said bottle neck having an inner horizontal plane surface bordered by a frusto-conical surface, a flat circular resilient sealing disk seated on the inner horizontal plane surface of the bottle neck, a brush disposed 50 within the bottle, said brush being secured to and supported solely by said disk, and a closure cap threaded to the bottle neck to hold said disk in sealing relation thereto, said closure cap comprising a frusto-conical inner surface for cooperating with the frusto-conical surface of the neck to press the margin of said disk therebetween, said cap having an inner chamber 55 centrally disposed relative to the frusto-conical surface thereof for the reception of a part of the disk when in a final sealed position, the inner diameter of the threads of said cap being less than the diameter of said disk, the latter being forceable past the threads when the cap is applied.
